RAZOR BLADE CHANGER

James M. Austin, Old Westbury, N. Y.

Application June 3, 1950, Serial No. 165,917

7 Claims. (Cl. 30—40)

1

This invention relates to razor blade changers. It is an object of the invention to provide a blade changer of inexpensive construction, but which is adapted to performing an automatic blade change with certainty and simplicity of operation.

With this and still other objects which will appear in the following full description in mind, the invention consists in the combinations and arrangements of parts and details of construction which will now first be fully described with reference to the accompanying drawing and then be more particularly pointed out in the appended claims.

In the drawing:

Fig. 1 is a plan view of a blade changer with new and used blade magazines and a razor in place thereon;

Fig. 2 is a section in the line 2—2 of Fig. 1;

Fig. 3 is a plan view of the blade changer of Fig. 1, with magazines and razor removed; and

Fig. 4 is a section on the line 4—4 of Fig. 1.

In my application Ser. No. 159,038, filed April 29, 1950, for Blade Changer, I have disclosed a blade changer, razor and magazines for use therewith. The present invention is an improvement thereon, the objects being to simplify the razor construction and provide a blade changer of simple construction which is adapted to mounting on a wall and requires no box or housing. The details of the magazines and the movement of parts in changing blades are disclosed fully in my said previous application and will be repeated only to the extent necessary to a full understanding of the present invention.

The complete equipment includes the blade changer frame A, razor B and new and used blade magazines C and D.

The frame A is formed from a sheet metal blank by stamping and similar power press operations. Projections 1, 2, 3 and 4 are struck up for holding the magazines, as indicated. Aperture 5 accommodates a tongue 6 on the magazine, the tongue 6 fitting under the plate A for holding down the magazine. Projection 4 is formed as a clip which snaps over an extension 7 at the other end of the magazine. The end wall 8 of the magazine is firmly held against projection 1 to position the magazine with reference to the razor B.

Razor B comprises a handle 10 in which are fixed the back member 11 and guard member 12, the parts being held together with handle 10 and ferrule 13, as by a rivet 14. Projections or lugs 15 on the guard extend through apertures

2

16 in the back so that when the razor is positioned as shown in Figs. 1 and 2 the supporting plate A will engage the lugs 15, forcing the guard 12 away from the back 11 so as to release the blade. A tongue 17 is formed on the back and passes through an aperture 18 in the guard, hooking under the upper edge of this aperture as shown for holding the guard in position at this point. When lugs 15 are engaged as shown in Fig. 2 the upper end of the guard will pivot on tongue 17, so that the corner lugs 19 on the guard disengage the blade 20, permitting sliding of the blade out of the razor by movement parallel to its cutting edge and reception of a new blade by a like sliding movement. It has been found that, if the guard 12 is made of sufficiently springy metal, a separate spring element for urging the back and guard together may be dispensed with. There is thus produced an exceptionally simple razor having only two parts, apart from the handle structure.

The means for holding the razor on the blade changer plate A comprises hooks or ledges 21 fitting over the cap portion 22 of the back 11; clip 23 passing through aperture 18 on the guard and a registered aperture in the back so as to snap over tongue 17 and hold the back down on the plate A; and an abutment 23' for supporting the back 11 down toward the handle 10. The razor is inserted in the blade changer by placing the cap under ledges 21 and then forcing the handle down until clip 23 catches. The razor is removed by reversing these movements, first lifting the handle to disengage from clip 23 and then sliding the cap out from under ledges 21.

Brackets 26 carry a rod 27 on which is slidably and pivotably mounted a pusher 28. Pusher 28 has a tongue 29 adapted to enter a slot in the magazine C and to engage against the back end of the top blade of a stack of blades. Details of this structure are fully shown in my above mentioned application and will not be repeated herein. Part of the pusher is struck up at an angle, as indicated at 30, to facilitate operation by the thumb or finger.

Each time the pusher is operated from right to left, a new blade is injected in the razor B from magazine C, pushing the used blade from the razor into magazine D. When the magazine C is exhausted and the magazine D is filled with used blades, the latter is discarded and the empty magazine C is placed in the position previously occupied by magazine D. A full new blade magazine may now be placed in the location previously occupied by new blade magazine C. The slot

for dispensing new blades is indicated at 25 and the slot for receiving used blades at 24. It will be observed that, in the position of magazine C, the slot 25 is in line with the blade in the razor and, in the position of magazine D, the slot 24 is in line with the blade in the razor.

In order to provide space for the extensions 6 of the magazines and to stiffen the plate A and arrange it at a proper angle, a rear flange wall 31 is bent down from the plate as well as end flange walls 32. The latter are made triangular in form, as shown, for locating plate A and a razor carried thereon at a desired angle.

The plate A may be held in the hand or rested on a table while the blade change is being made, but is intended for mounting on a wall as in a bathroom. Screw holes 33 are formed in the plate to accommodate screws 34 by means of which the plate is fastened to a wall 35 as indicated in Fig. 2. Assuming the wall 35 to be vertical, the upper end of the plate A will be positioned outwardly and the plate will slant backwardly toward the wall, as shown. This brings the handle 10 of the razor in toward the wall 35. The plate A may also be fastened to a horizontal surface where desired, and in this case the slanting of the plate also brings the handle of the razor closer down to the surface.

To assist in maintaining blade alignment, the pusher tongue 29 is located closer to the cutting edge of the blade than to its back edge, as indicated in Figure 4, this arrangement tending to hold the back edge of the blade against the wall of the magazine during ejection. The same result can be achieved by slanting the blade engaging edge of a centrally placed tongue 29, if desired. Since the blades and razor cap are at right angles to the plate, it will be apparent that the device will work satisfactorily in either a vertical or horizontal support.

What is claimed is:

1. A blade changer comprising a plate adapted for wall mounting and having means for holding a new blade magazine, a razor and a used blade magazine in aligned position for a blade change, with the back of the razor against the plate and the cap at substantially right angles thereto, and a slideable pusher arranged for pushing the top blade of a stack in the new blade magazine into the razor to effect a blade change.

2. A blade changer comprising a plate adapted for wall mounting and having integral parts struck up to form means for holding a new blade magazine, a razor and a used blade magazine in aligned position for a blade change, and a slideable pusher arranged for pushing the top blade of a stack in the new blade magazine into the razor to effect a blade change.

3. A blade changer comprising a plate adapted

for wall mounting and having means for holding a new blade magazine, a razor and a used blade magazine in aligned position for a blade change, and a slideable pusher arranged for pushing the top blade of a stack in the new blade magazine into the razor to effect a blade change, the plate also having apertures for receiving magazine positioning elements and permitting insertion thereof under the plate and means on the back of the plate to space it from a wall.

4. A blade changer comprising a plate adapted for wall mounting and having means for holding a new blade magazine, a razor and a used blade magazine in aligned position for a blade change, with the blades at substantially right angles to the plate, and a slideable pusher arranged for pushing the top blade of a stack in the new blade magazine into the razor to effect a blade change, and means for holding an edge of the plate away from a wall to slant the plate for bringing the handle of a razor held on the plate closer to the wall.

5. A blade changer comprising a plate adapted for wall mounting and having means for holding a new blade magazine, a razor and a used blade magazine in aligned position for a blade change, with the back of the razor against the plate and the cap at substantially right angles thereto, and a slideable pusher arranged for pushing the top blade of a stack in the new blade magazine into the razor to effect a blade change, and means for holding an edge of the plate away from a wall to slant the plate for bringing the handle of a razor held on the plate closer to the wall.

6. A blade changer comprising a plate adapted for wall mounting and having integral parts struck up to form means for holding a new blade magazine, a razor and a used blade magazine in aligned position for a blade change, and a slideable pusher arranged for pushing the top blade of a stack in the new blade magazine into the razor to effect a blade change, the plate also having flange edges struck downwardly to support the same in spaced relation from a wall.

7. A blade changer according to claim 6, in which the said flange edges are proportioned to hold the blade changer in slanted position on a wall for bringing the handle of the razor held thereon closer to the wall.
